HAND TRUCK FOR VACUUM CLEANER AND ACCESSORIES

Joseph G. Haworth, Los Angeles, Calif.

Application July 11, 1947, Serial No. 140,222

Term of patent 7 years

(Cl. D14—3)

To all whom it may concern:

I, Joseph G. Haworth, a citizen of the United States, residing at Los Angeles, county of Los Angeles, State of California, have invented a new, original, and ornamental Design for Hand Truck for Vacuum Cleaner and Accessories, of which the following is the specification, reference being had to the accompanying drawing, constituting a part hereof.

Fig. 1 is a perspective view of a hand truck for vacuum cleaner and accessories, showing my new design;

Fig. 2 is a side elevation of the hand truck shown in Fig. 1; and

Fig. 3 is a plan view of the hand truck shown in Fig. 1.

I claim:

The ornamental design for a hand truck for vacuum cleaner and accessories, substantially as shown.

JOSEPH G. HAWORTH.
